UNITED STATES PATENT OFFICE.

LOUIS P. GERHARDT, OF LORAH, IOWA.

LONG-RANGE SHOT-GUN CARTRIDGE.

1,243,155.

Specification of Letters Patent. Patented Oct. 16, 1917.

Application filed November 22, 1916. Serial No. 133,259.

To all whom it may concern:

Be it known that I, LOUIS P. GERHARDT, citizen of the United States of America, and resident of Lorah, Cass county, Iowa, have 5 invented a new and useful Long-Range Shot-Gun Cartridge, of which the following is a specification.

The object of this invention is to provide an improved construction for long-range 10 cartridges adapted to maintain a quantity of shot in compact relations for a considerable time after leaving the muzzle of the gun.

A further object of this invention is to 15 provide an improved construction for a shot container.

A further object of this invention is to provide improved yielding means for retaining 20 a shot container in the cartridge.

25 My invention consists in the construction, arrangement and combination of elements hereinafter set forth, pointed out in my claims and illustrated by the accompanying drawing, in which—

30 Figure 1 is a longitudinal sectional elevation of the preferred form of my improved cartridge. Fig. 2 is a front end view of the same. Fig. 3 is a longitudinal sectional elevation of a cartridge illustrating a slightly modified form of shot container, in which a metallic liner is employed. Fig. 4 is a 35 side elevation of a further modified form of shot container.

In the construction of the device as shown 40 particularly in Figs. 1 and 2 the numeral 10 designates the usual casing or shell formed of thin metal, provided with a firing cap 11, and supplied with a quantity of explosive 12 such as powder in its base. A wad 13 of common form is mounted in the shell or 45 casing 10 over the charge 12. A shot container 14 is provided and is mounted in the casing 10 and rests on the wad 13, and said container is formed of pasteboard or fiber- 50 board, is of tubular form, open at its base and closed at its forward end; and said container holds a quantity of shot such as 55. The container 14 is formed with a cone-shaped head 16 at its forward end lying within the forward end portion of the shell 10. The shell or casing 10 is formed with diametrically opposed longitudinal slots 17, 18 near and opening to its forward end, from which slots spring tongues 19, 20 are 60 bent inwardly to engage the head 16 of the shot container. It is the function of the

60 springs 19, 20 to retain the shot container 14 within the shell or casing 10, but to yield and permit the passage of such container when the charge 12 is exploded.

In practical use the container is ejected 65 from the shell when the gun is fired and passes through and out of the gun barrel, and proceeds a considerable distance from the muzzle of the gun in its normal position; that is, with the head 16 in advance, thus retaining the charge 15 of shot in compact relations and preventing scattering of such shot. When the container 14 has proceeded a certain distance from the gun, usually from forty to fifty yards, the resistance 70 of the air currents causes it to turn over, after which the shot 15 continue on their way and the container 14 drops to the ground. This enables the shot to be delivered 75 within a small radius at a considerable distance from the gun, and the result is consequently more effective at long range than where they are permitted to commence scattering as soon as they issue from the gun. 80

I am aware that other shot containers 85 have been made having square or hemispherical noses or heads, but I have demonstrated by actual experiment that the cone-shaped head is much more effective in carrying the shot a longer distance, and that the container so constructed will not turn over as soon as a square or round headed container. 90

As the shell or casing 10 is formed of relatively thin material, the container 14 fits quite snugly to the gun barrel after leaving the shell. 95

In the construction according to Fig. 3 a liner 21 is employed within the shot container 14 and said liner preferably is formed of thin sheet metal. It is fitted snugly to and within the container and receives the actual contact of the shot 15, and also serves to strengthen and reinforce the container. 100

In the construction shown in Fig. 4 I have 105 illustrated the shot container 14 having a head 16 which is substantially cone-shaped, but the tip is blunted or rounded slightly. With this construction the container will turn more quickly than where it has the pointed head. In other respects this construction is identical with that previously described in connection with Figs. 1 and 2, and the liner shown in Fig. 3 may or may 110 not be employed as is found to be most desirable.

I claim as my invention—

1. A long-range cartridge, comprising a shell open at one end, a shot container mounted therein, said shot container being open at its base and being formed with a cone-shaped head lying within the open end of said shell, and spring tongues cut out from the forward end of said shell and engaging said cone-shaped head.
- 10 2. A long-range cartridge, comprising a thin-walled shell, a pasteboard shot container mounted therein, said container being open at its base and formed with a cone-shaped head, a metallic liner within said container, and spring tongues on the forward end of said shell bent inwardly at

acute angles and yieldingly engaging said container.

3. A long-range cartridge, comprising a shell, a tubular shot container mounted therein and having a cone-shaped head within the open end of said shell, and diametrically opposed spring tongues cut from the forward portion of said shell and bent inwardly at acute angles and engaging 25 said cone-shaped head.

Signed by me at Lorah, Iowa, in the presence of two witnesses.

LOUIS P. GERHARDT.
